J. W. TRACY, OF ST. LOUIS, MISSOURI.

Letters Patent No. 71,428, dated November 26, 1867.

IMPROVEMENT IN GAS CIGAR-LIGHTERS.

The Schedule referred to in these Letters Patent and making part of the same.

TO ALL WHOM IT MAY CONCERN:

Be it known that I, J. W. TRACY, of St. Louis, in the county of St. Louis, and State of Missouri, have invented a new and improved Cigar-Lighter; and I do hereby declare that the following is a full, clear, and exact description thereof, which will enable others skilled in the art to make and use the same, reference being had to the accompanying drawing, forming part of this specification.

The present invention relates to a cigar-lighter, which consists of a figure or ornament intended to sit on a till, or other suitable place, in a saloon. The figure or ornament is connected with a gas-pipe by a flexible tube, which will be understood from the following:

a, in the drawing, represents a metal figure, with a pipe in its mouth. The figure has a hole through its length, from the mouth to the pedestal, and is connected to the gas-pipe *b* by the flexible tube *c*. *d* is a stop-cock, with a weighted lever, *e*, running through its key. At one end of this lever an elastic cord, *f*, is attached, which passes around the fixed pulleys *g g*, and attached to the flexible tube at *h*. The elastic cord *f* will pull sufficiently on the lever *e* to keep the stop-cock slightly open, and thus allow a small flame to be kept burning in the pipe *i*, which is held in the mouth of the figure.

When a light is required, the figure is picked up, and, in doing so, it will cause the elastic cord *f* to be pulled, which will draw down the lever *e*, and thus open the stop-cock, which will allow a full head of gas to flow through the pipe, which will enable a person to get a good, even light, instead of only half lighting the cigar, by the old method of using a torch and alcohol, besides my method being so much cheaper, for, when not in use, the gas is turned down low.

I do not limit myself to any particular kind of figure, or part thereof, whereby to obtain the light.

Having thus described my invention, what I claim as new, and desire to secure by Letters Patent, is—

The figure *a*, attached by the flexible tube *c* to the gas-pipe *b*, in combination with the elastic cord *f*, operating on the weighted lever *e*, in the manner and for the purpose substantially as shown and described.

The above specification of my invention signed by me, this 9th day of May, 1867.

J. W. TRACY.
